HOOD CATCH

Raymond G. Moore, Bridgeport, Conn., assignor
to The Bassick Company, Bridgeport, Conn., a
corporation of Connecticut

Application March 20, 1933, Serial No. 661,654

4 Claims. (Cl. 292—87)

The present invention relates to hood catches for securing the hoods of automobiles, and has for an object to provide a hood catch of extremely simple and inexpensive construction, which 5 may be operated with facility, and will effectually hold the hood downwardly and inwardly against looseness and rattling. Another object is to provide a hood catch in which the handle and catch means will be exteriorly disposed while the tensioning mechanism is interiorly disposed, thus providing a catch which may be easily and positively operated, and which at the same time will present a neat and inconspicuous appearance free from unsightly mechanism, and which lends 10 itself to streamline design harmonizing with other parts of the automobile structure.

A further object is to provide a hood catch which will be free from loose parts, and in which the resiliency for holding the hood downwardly and inwardly is a function of an integral part of the catch proper, as distinguished from other types of catches in which extraneous spring elements are employed. To this end it is proposed to provide a handle and catch bar in the form 20 of a resilient rod having an integral coil spring portion at one end disposed at the side of the hood, the handle and catch portions being at the outside and adapted to be sprung into engagement with a keeper on the cowl or radiator frame.

A further object is to provide a catch which may be horizontally disposed, out of relation with the sill, so that it may be conveniently reached and will in no way interfere with other parts of 30 the automobile.

A still further object is to provide a hood catch which will utilize the springiness of the metal of the hood side to exert inward holding pressure.

With the above and other objects in view an embodiment of the invention is shown in the accompanying drawing and this embodiment will be hereinafter more fully described with reference thereto, and the invention will be finally pointed out in the claims.

In the drawing:

Fig. 1 is a front elevation of one corner of an automobile hood and the adjacent cowl and sill structure, and showing the hood catch according to the illustrated exemplary embodiment of the invention attached thereto.

Fig. 2 is a vertical sectional view, taken along the line 2—2 of Fig. 1, and showing the catch in end elevation.

Fig. 3 is a horizontal sectional view taken along

the line 3—3 of Fig. 1, the catch being shown in top plan.

Fig. 4 is a horizontal sectional view taken along the line 4—4 of Fig. 1, the bar being shown disengaged from the keeper.

Fig. 5 is a rear elevation of the catch showing the inoperative position, and also showing in dot-and-dash lines the operative keeper engaging position.

Fig. 6 is a fragmentary vertical sectional view 10 showing a modified form of keeper and catch bar.

Fig. 7 is a diagrammatic horizontal sectional view of the hood and the adjacent structure of the radiator and cowl, showing in exaggeration the 15 flexing of the hood in the operative position of the catch according to the modification shown in Fig. 5.

Similar reference characters indicate corresponding parts throughout the several figures of 20 the drawing.

Referring to the drawing, the hood 10 is adapted to close in the usual manner against lacings 11—11, provided along the inset marginal edge portions 12—12 of the radiator and cowl structure 13—13, and at each end of the hood, and adapted to cooperate with keepers provided on the radiator frame and cowl structures, hood catches according to the illustrated exemplary embodiment of the invention are mounted.

The hood catch comprises a rectangular mounting plate 14 provided with a bearing opening 15 having an outwardly bent flange engaged in an opening 16 in the hood. An escutcheon plate 17 having a peripheral inwardly bent flange 35 is provided centrally with a bearing opening 18 flanged inwardly and disposed in axial alignment with the opening 15. A pair of securing studs 19—19 are welded to the inner side of the escutcheon plate and extend through piercings in 40 the hood 10 and plate 14, being headed over upon the plate 14 to thus securely attach the mounting plate 14 to the inner side of the hood and the escutcheon plate to the outer side. The mounting plate is preferably adjacent one of the lower corners, although if desired it may be at a substantially higher point than that illustrated.

The hood catch proper is in the form of a single bent bar of spring metal, the inner end portion being disposed upon the mounting plate 14 50 and being in the form of a coil spring 20, its outer angularly bent end 21 being secured beneath a strap portion 22 struck up from the plate 14 and its inner end being bent forwardly as at 23 through the bearing openings 15 and 18 to the 55

outer side of the hood, where it is again bent and extends longitudinally of the hood to provide a spring handle and catch bar portion, the handle portion 24 being arcuately bent outward to facilitate engagement by the fingers and the catch portion 25 being straight and extending beyond the end of the hood. In the inoperative disengaged position the bar stands outwardly from the hood at a slightly inclined angle to the hood surface, as shown in Fig. 4, and also is inclined upwardly from the horizontal operative position as shown in full lines in Fig. 5, and is adapted to flex both vertically and transversely, the vertical flexing being a function of the coil spring portion 20, which winds as the bar is depressed and unwinds as it is raised.

The keeper comprises a base plate 26 and a right angularly bent hook flange 27, having a catch engaging recess 28 provided with an angular camming surface. The plate is preferably secured at the inner side of the cowl or radiator frame 13, as by rivets 29, and the flange 27 projects to the outer side through a slot opening 30 in the cowl or frame.

25 In operation, the hood is drawn downwardly by downward pressure on the handle portions 24 at each end, these being sufficiently stiff for the downward pressure to be firmly transmitted to the hood, so that it can be effectually pressed down to its full limit with facility.

30 During this action the bar is pressed downwardly below the horizontal operative position as shown in dot-and-dash lines in Fig. 1 and is then pressed under the nose of the keeper into the recess 28, where its inherent resiliency springs the catch end upwardly along the inclined surfaces of the recess drawing the hood downwardly and inwardly under the vertical and transverse tension of the bar. To disengage the catch bar 40 is pressed downwardly and pulled outwardly to disengage the catch end, the bar springing to the position indicated in full lines in Figs. 4 and 5.

In Fig. 6 I have shown a modified form of keeper 27^a having a recess 28^a provided with a vertical outer wall. In this case the handle and catch bar 24^a—25^a is rigid transversely, and is normally disposed in its inoperative position at an angle to the hood in a similar manner to the inoperative position of the bar 24 of the first embodiment as shown in Fig. 4, and is pressed inwardly to engage the keeper recess. In this case the bar 24^a—25^a may be made of more rigid metal than that employed in the first embodiment so that transverse pressure thereon will 55 flex the hood rather than the bar, or alternatively the bar 24^a—25^a may be of the same metal as the first embodiment and the hood 10 upon which it is mounted may be relatively more flexible than the hood 10 of the first embodiment. In either case the hood will be relatively flexible and the bar will be relatively stiff transversely. The ends of the hood being supported against the lacings 11, and the bar being rigid transversely the inward pressure of the bar causes the hood to be 60 slightly sprung or warped, as indicated diagrammatically in Fig. 7, and being held in this position by engagement of the catch end in the keeper the inherent springiness of the sheet metal of the hood exerts an inward pressure upon the hood thus pressing it inwardly firmly against the lacings.

I have illustrated and described a preferred and satisfactory embodiment of the invention, but it will be obvious that changes may be made therein,

within the spirit and scope thereof, as defined in the appended claims.

Having thus described my invention what I claim and desire to secure by Letters Patent is:—

5 1. An automobile hood catch for mounting on the hood to engage a keeper disposed upon a fixed part in relation to the end of the hood and having a downwardly disposed catch engaging surface, the hood in its closed position being limited in its downward movement by engagement with a fixed part, comprising a bar adapted to be secured at one end to the hood and including an integral coil spring portion adjacent said secured end, its other end including a keeper engaging portion normally disposed above the catch engaging surface of the keeper in the closed position of the hood, and adapted in said closed position to be sprung downwardly to pull the hood down against said fixed part and to engage said keeper through upward springing of said bar, the sprung bar adapted to exert a continuous downward pressure on the hood.

10 2. An automobile hood catch for mounting on the hood to engage a keeper disposed upon a fixed part in relation to the end of the hood and having a downwardly disposed catch engaging surface, the hood in its closed position being limited in its downward movement by engagement with a fixed part, comprising a mounting fixture 15 adapted to be secured interiorly of the hood, and a bar rigidly secured at one end to said mounting fixture and including an integral coil spring portion adjacent said secured end, the inner end of said coil spring portion being bent outwardly from said fixture to the exterior of the hood and extending longitudinally and beyond the end of the hood, said portion extending beyond the end of the hood being normally disposed above the catch engaging surface of the keeper in the closed position of the hood, and adapted in said closed 20 position to be sprung downwardly to pull the hood down against said fixed part and to engage said keeper through upward springing of said bar, the sprung bar adapted to exert a continuous 25 downward pressure on the hood.

3. An automobile hood catch for mounting on the hood to engage a keeper disposed upon a fixed part in relation to the end of the hood and having downwardly and inwardly facing catch

30 engaging surfaces, the hood in its closed position being limited in its downward and inward movement by engagement with a fixed part, comprising a spring bar adapted to be secured at one end to the hood and including an integral coil spring portion adjacent said secured end, its other end including a keeper engaging portion normally disposed above and laterally outwardly of the catch engaging surfaces of the keeper in the closed position of the hood, and adapted in said closed 35 position to be sprung downwardly and inwardly to pull the hood down against said fixed part and to engage said keeper through upward springing of said bar, the sprung bar adapted to exert a continuous 40 downward and inward pressure on the hood.

4. An automobile hood catch for mounting on the hood to engage a keeper disposed upon a

45 fixed part in relation to the end of the hood and having downwardly and inwardly disposed catch 50 engaging surfaces, the hood in its closed position being limited in its downward and inward movement by engagement of its end portion with a fixed part, and said hood being inherently 55 resilient, comprising a bar adapted to be secured at one end to the hood and including an integral 60

coil spring portion adjacent said secured end, its other end including a keeper engaging portion normally disposed above and laterally outwardly of the catch engaging surfaces of the keeper in the closed position of the hood, said bar being springy in an up and down direction and transversely rigid, said bar adapted in said closed position to be pressed inwardly whereby said hood

is warped and to be sprung downwardly to pull the hood down against said fixed part and to engage said keeper through upward springing of said bar, the sprung bar adapted to exert a continuous downward pressure on the hood, and the warped hood exerting a continuous inward pressure thereon.

RAYMOND G. MOORE.
